ARNOLD EGLI, OF AUGSBURG, GERMANY, ASSIGNOR TO MASCHINENFABRIK AUGSBURG-NÜRNBERG, AKTIENGESELLSCHAFT, OF AUGSBURG, GERMANY, A CORPORATION OF GERMANY.

MACHINE FOR TRIMMING STEREOTYPES.

1,180,116.

Specification of Letters Patent.

Patented Apr. 18, 1916.

Application filed March 18, 1915. Serial No. 15,392.

To all whom it may concern:

Be it known that I, ARNOLD EGLI, a citizen of the Swiss Confederation, and residing at Augsburg, Germany, have invented certain new and useful Improvements in Machines for Trimming Stereotypes, of which the following is a specification.

This invention relates to machines for trimming stereotypes.

10 In known machines of the type in question the dead head of the plate is cut off by a milling cutter rotating about its own axis. The metal cut away by the rapidly rotating cutter is almost as fine as dust and is thrown away from the tool. This metallic dust flies about in the air, penetrates into bearings and other readily injured parts of machines and causes trouble. Further, the fine particles flying about in the air are a great annoyance to the mechanics in charge of the machines. Also, a high percentage of valuable metal is lost.

15 A primary object of this invention is to provide an improved machine for trimming stereotype plates to which these defects are not attached.

To this end, in the improved machine according to the invention the dead head is removed not as described above by a cutter 30 rotating about its axis, but by one or more edging tools such as are used in well-known manner in tooling iron, brass and other materials. The edging tools are preferably carried by a tool carrier which rotates about 35 the stereotype. When this mode of removing superfluous metal is adopted the waste metal has the form of long shavings which can be caught in a box. Further, as compared with the milling cutters used heretofore the tools employed in the improved machine 40 according to the invention have the advantage that the work proceeds almost noiselessly, whereas the high-speed milling cutter causes a very loud noise which is very 45 disagreeable, particularly at night.

The tool carrier in the improved machine is preferably provided with two different kinds of tools, the one being adapted for cutting off the dead head, and the other for 50 making faces of exactly predetermined shape.

To these ends the invention consists in the construction, arrangement and combination of parts described hereinafter and pointed 55 out in the claims.

One illustrative embodiment of the invention is diagrammatically represented by way of example in the accompanying drawings, wherein:

Figure 1 is an elevation, partly in section, 60 showing a preferred form of the improved machine, part being shown broken away, and Fig. 2 is a vertical section through the upper part thereof; Figs. 3 and 4 are plans and elevations, respectively, showing the 65 two different kinds of edging tools, and Fig. 5 is an enlarged sectional view showing how the tool carrier is mounted.

Referring to the drawing, the stereotype plate *a* rests on the two ledges *b* and *c* while 70 it is being tooled, it being held in position during the tooling operation by the cylindrical support *d* (Fig. 2); the stereotyped impression is prevented in known manner from being injured owing to a sheet *e* of 75 zinc being placed between the support *d* and the plate *a*. The parting tools proper are designated *f*, and the bordering tools *g*. Both kinds of tools are mounted on the rotatable carrier *h* which, in the illustrative 80 embodiment, has a toothed external periphery, is mounted in the manner described hereinafter and is driven by the chain *i*. The tools *f* and *g* are inserted into radial slots *k* in the carrier *h* and are prevented 85 from shifting axially by the disk *l*. Each tool has a lug *m* which takes into a groove *n* in the disk *l*. In this manner the tools are also prevented from unintentionally shifting radially. The disk *l* in turn, is prevented 90 from shifting axially by the disk *o* which is securely fastened by the screws *p* to the carrier *h*.

The carrier *h* and the disk *l* do not rotate at the same speed; on the contrary, the disk *l* 95 is driven by the carrier *h* or by the disk *o* through the intermediary of a gear-wheel *q* in such manner that it moves relatively to the disks *h* and *o*. The arrangement may suitably be such that the disk *l* rotates 321 100 times while the members *h* and *o* rotate 320 times. The disk *l* therefore rotates relatively to the tools *f* and *g*. The lugs *m* of the tools slide in the cam-ways *n* in the disk *l*. During the tooling operation the 105 tools are therefore slowly driven radially forward until the dead head is completely separated and the tooling of the faces is finished; on the termination of this operation they are slowly returned into their ini- 110

tial position owing to the action of the cam-way on the lugs m . For example, if the tool carrier rotates 40 times until the plate is completely tooled, and if there is the above mentioned ratio of transmission 321:320 between the disks l and o , then the disk l will rotate $\frac{1}{8}$ revolution relatively to the tool carrier during the tooling of a plate. Accordingly, during the first 20 revolutions of the tool carrier the tools are fed forward and during the second 20 revolutions returned into their normal position when the cam-way has the shape shown in the drawing. The drawing shows the tools in their lowest position at the moment when the head has been completely separated from the plate.

The rotatable tool carrier is adjustably mounted on the fixed frame d of the machine by means of ball-bearings r provided in the recesses s in the disk h . Fig. 5 shows one of the bearings on an enlarged scale. Rigidly secured to the disk h are eccentric pins v which are carried by ball-bearings r . The ball-bearings are held in position by plates y which are securely held on the disk h by the screws z . The outer periphery of each of the outer rings t of the ball-bearings runs on the cylindrical periphery of the stationary member u which is integral with the frame or support d or is rigidly connected therewith. By turning the eccentric pins v the rings t can be readily adjusted. After the ball-bearings r have been correctly adjusted the tool carrier will run exactly concentrically with the plate a .

After the separation of the dead head is complete, thus in the present case after 20 revolutions of the tool carrier, the boring tool w operates and bores out the inside of the plate. This tool rotates once while the tool carrier h rotates 40 times. While the inside of the plate is being bored out the tool carrier h runs light, the edging tools f and g being returned into their normal position during this time. The inside of the plate is tooled only after the complete separation of the dead head x because otherwise the heavy dead head would load one end of the plate during the boring operation and the plate might not bear evenly against its support while the inside is being tooled.

I claim:—

1. In a machine for trimming curved plates, the combination with a support for a plate, of a tool carrier rotatably mounted on the support, and severing tools carried by the tool carrier for cutting the plate in two, bordering tools slidably carried by the tool carrier for trimming the cut off edge of the plate, and means for radially advancing and retracting the cutting edge of the tools during the rotation of said carrier.

2. In a machine for cutting and trimming cylindrically curved plates, the combination

with a cylindrical support for a plate, of a tool carrier rotatably mounted on the support, severing tools slidably carried by the tool carrier for cutting the plate, and bordering tools slidably carried by the tool carrier for trimming the cut off edge.

3. In a machine for trimming cylindrically curved plates, the combination with a rigid support for a plate, of a tool carrier rotatably mounted on the support, and severing knife tools slidably carried by the tool carrier and adapted to sever the plate, a boring tool adapted to shave the inner side of the plate mounted rotatably and concentrically with the said tool carrier and gearing connection between said tool carrier and said boring tool whereby said boring tool is made to operate during half a revolution after the severing tools have completed their work.

4. In a machine for trimming cylindrically curved plates, the combination with a fixed cylindrical support for a plate, of a tool carrier rotatably mounted on the support, and severing tools slidably carried by the tool carrier and adapted to sever the inner side of the plate mounted rotatably and concentrically with the said tool carrier and connected in such a manner with the tool carrier that it is brought in working position in a half revolution while the tools sever the plate and begins to work when the severing operation is finished.

5. In a machine for trimming cylindrically curved plates, the combination with a cylindrical support for a plate, of a rotatable tool carrier mounted on the support, means for relative adjustment between the carrier and the support comprising eccentric bolts having antifriction bearings and a clamping device for the bolts, and edging tools slidably carried by the tool carrier and adapted to tool the curved edge of the plate.

6. In a machine for trimming semicylindrical stereotype plates having a dead head on the curved edge thereof, the combination with a cylindrical support for a plate, of a radially slotted tool carrier rotatably mounted on the support, a disk rotatably mounted on and geared to the tool carrier, said disk being provided with a cam-way of polygonal shape, and tools inserted into the slots in the tool carrier, each tool having a lug taking into the cam-way, whereby the tools will be automatically advanced and retracted in radial direction during the rotation of said carrier.

7. In a machine for trimming semicylindrical stereotype plates having a dead head on the curved edge thereof, the combination with a cylindrical support for a plate, of a circular tool carrier, a plurality of eccentric pins carried by the latter, each pin carrying a ball-bearing comprising an outer ring

adapted to run on a cylindrical outer face of the support, and radially disposed edging tools carried by the tool carrier.

8. In a machine for trimming semicylindrical stereotype plates having a dead head on the curved edge thereof, the combination of a cylindrical support, a radially slotted tool carrier adjustably mounted thereon, a disk having a cam-way rotatable on the tool carrier, gearing having a small ratio of transmission operatively connecting the tool carrier with said disk, parting tools and bordering tools mounted in the slots in the tool carrier, each tool having a projection taking into the cam-way.

9. In a machine for trimming cylindrically curved plates, a fixed support for the plate, an arbor revolvably mounted in said support, a boring tool on said arbor, an annular carrier having a radial recess, a knife tool slidably mounted in said recess and provided with a transverse lug, a cam ring having a straight tangential cam groove engaging with said lug, said arbor, carrier and cam ring being concentrically mounted on said support and provided with positive driving connection, whereby said lug and cam groove will coöperate to advance said knife tool to do its cutting while said boring tool runs idle, and thereupon retract the knife tool while the boring tool is in operation.

10. In a machine for trimming cylindrically curved plates, a fixed support for the plate, an arbor revolvably mounted in said support, a boring tool on said arbor, an annular carrier having a radial recess, a knife tool slidably mounted in said recess and provided with a transverse lug, a cam ring having a straight tangential cam groove engaging with said lug, said arbor, carrier and cam ring being concentrically mounted on said support and provided with positive driving connection, the ratio of which is such, that said lug travels the entire length

of said cam groove while said arbor makes one revolution.

11. In a machine for trimming cylindrically curved plates, a fixed support for the plate, an arbor revolvably mounted in said support, a boring tool on said arbor, an annular carrier having a radial recess, a knife tool slidably mounted in said recess and provided with a transverse lug, a cam ring having a straight tangential cam groove engaging with said lug, said arbor, carrier and cam ring being concentrically mounted on said support and provided with positive driving connection, the ratio of which is such, that said lug travels the entire length of said cam groove while said arbor makes one revolution thereby advancing and retracting the knife tool once while said boring tool respectively runs idle and does its work.

12. In a machine for trimming cylindrically curved plates, a fixed support for the plate, an arbor revolvably mounted in said support, a boring tool on said arbor, an annular carrier having eight radial recesses, a knife tool slidably mounted in each of said recesses and provided with a transverse lug, a cam ring having a continuous cam groove in the shape of an octagon in which all of said tool lugs engage, said arbor, carrier and cam ring being concentrically mounted on said support and provided with positive driving connection, the ratio of which is such that said boring tool makes one half revolution while the eight knife tools are simultaneously advanced by said lugs and cam groove, and the boring tool makes another half revolution while the eight knife tools are similarly retracted.

In testimony whereof, I affix my signature in the presence of two witnesses.
